TABULATING MECHANISM

Elmer L. Wise, Bridgeport, Conn., assignor to Underwood Corporation, New York, N. Y., a corporation of Delaware

Application February 4, 1950, Serial No. 142,438

7 Claims. (Cl. 197—178)

1

This invention relates to typewriting machines of the class wherein the type head or carriage is tabulated to various columnar positions upon the depression of any one of a plurality of keys, and more particularly to means for tabulating the carriage by power under control of the keys.

One of the objects of the present invention is to provide a mechanism which, upon the depression of certain keys, is connected with power means to positively operate an escapement mechanism and tabulate the carriage.

Another object of the invention is to provide a power driven escapement operating mechanism which is operable by either a space bar or by any of a group of tabulator keys.

Still another object of the invention is to provide, as a part of a tabulating mechanism, a power driven escapement operating mechanism which is simple in construction and reliable in operation.

With these and incidental objects in view, the invention consists in certain novel features of construction and combinations of parts, the important elements of which are set out in the preferred embodiment of the invention hereinafter described with reference to the drawings accompanying and forming part of this description.

In the drawings:

Figure 1 is a view in vertical section of a machine embodying the invention and particularly illustrating the escapement operating mechanism occupying its normal position.

Figure 2 is a fragmental view in rear elevation illustrating the escapement in its normal or carriage movement restraining position.

Figure 3 is a fragmental detail view showing certain of the parts shown in Figure 2 in the position they assume upon the depression of a tabulator key.

Figure 4 is a fragmental detail view showing certain of the parts of Figure 1 in actuated position, and

Figure 5 is a perspective showing of the central part of the mechanism shown in Figure 1.

The invention is illustrated and described herein as embodied in an Elliott-Fisher Flat Platen Typewriting and Accounting machine of the type disclosed in U. S. Patent No. 1,280,697, issued to Harry A. Foothorap, October 8, 1918, and in U. S. Patents Nos. 2,239,023 and 2,370,505, issued to Oscar J. Sundstrand, April 22, 1941 and February 27, 1945, respectively, to all of which patents reference may be had for an understanding of features of construction not fully illustrated or described herein.

2

Such machines include, generally, a line space frame mounted for forward and rearward movement over a flat platen arranged to receive and hold a work piece. A type head or carriage is mounted on the line space frame for movement in letter spacing direction under the urge of a band spring, and for return movement thereon by means of power supplied by an electric motor. The type head or carriage includes type bar mechanisms which, upon the depression of the usual keyboards, are selectively connected with the power means to drive the types into contact with the work piece and to operate an escapement mechanism for advancing the carriage letter space by letter space in the manner disclosed in the Patent No. 2,370,505 referred to. It also includes a space bar arranged to operate the escapement mechanism in substantially the same manner as is disclosed in the Patent No. 2,239,023 previously referred to.

In the illustrated construction, the carriage structure only is shown, comprising a plate 10 on which is mounted brackets 11 and 12 supporting an escapement shaft 13. Rotatably mounted on the shaft 13 is a gear 14 meshing with a rack 15, rigid in the line space frame (not shown). Affixed to the gear 14 is an escapement wheel 16 having teeth 17 spaced so as to provide the desired letter spacing of the carriage. A dog 19, pivoted at 18 in the bracket 11, normally engages the teeth 17 of escapement wheel 16, as shown in Figure 2, to position the carriage in a columnar position over the work piece. Tabulation of the carriage is effected by rocking the dog 19 from engagement with the teeth 17 of the escapement wheel 16 as is shown in Figure 3, whereupon the carriage is free to be advanced by means of the band spring previously mentioned.

Mounted on the plate 10 are carriage frame members 20, one at each side thereof, tied together by means of a top plate 21, Figure 1, plate 21 carrying upper frame members 22 in which is journalled a continuously driven fluted shaft 23. A plurality of decimal tabulator keys 25 are pivoted at 24 on the under side of plate 21 and are normally urged upwardly by individual springs 27 to stop against the underside of the plate 21. Two other keys, a carriage release key 29 and a column tabulator key 31 are pivoted in the frame members 20 on shafts 28 and 30 respectively.

The present invention provides means to move dog 19 from engagement with the teeth 17 of the escapement wheel 16 by power upon the depression of any one of the keys 25, 29 and 31.

The space bar mechanism

The machine disclosed in the above noted patents to Foothorap and Sundstrand includes means operated by a space bar 35, Figures 1 and 5, to momentarily release the escapement dog 19 from the teeth 17 of escapement wheel 16 to permit letter space movement of the typing head. In the present embodiment, this mechanism comprises the space bar 35 mounted on a pair of arms 36 connected by a yoke 37 across their rearward extension and freely pivoted on shaft 30. Another arm 38 pivoted on shaft 30 is connected to one arm 36 by a sleeve 39 and is perforated at its forward end to engage a pin 40 fixed in one side of a flanged flat plate 41 also pivoted on shaft 30. The other side flange of plate 41 is forwardly extended and is pivoted at 42 to a link 43 connected at its other end to an arm 44 pivoted on a shaft 45 and tensioned upwardly by a spring 46.

Arm 44 carries a stud 47 resting above an arm of a lever 48 pivoted adjacent arm 44 on shaft 45, the other arm of lever 48 extending upwardly into a slotted guide 49 and being tensioned rearwardly by a spring 50. Lever 48 carries an arm 51 projecting rearwardly therefrom, a spring 52 connected between the lever 48 and arm 51 serving to tension arm 51 clockwise against a stud 53 on a power lever 54 with a shoulder 55 of the arm 51 to the rear of stud 53. Lever 54 is similar to the levers for the type actions of the aforementioned patents and carries a snatch pawl 56 pivoted thereon for engagement with the fluted power shaft 23. Lever 54 is pivoted on a lever 57, pivoted in turn on a wire 58, a spring 59 connected between lever 48 and lever 54 normally holding lever 54 clockwise against a stop plate 60. Actuation of the space bar 35 will through the linkage set out rock levers 48 and 54 counterclockwise to engage snatch pawl 56 with the fluted shaft 23. Lever 54 will thereupon be driven downwardly rocking lever 57 about wire 58 until the pawl 56 disengages from shaft 23 after which spring 59 will act to restore the parts to the position of Figure 1 with the exception that if the space bar 35 is retained in depressed position, stud 53 will engage the arm 51 to the rear of shoulder 55.

Connected to the forward end of lever 57 and actuated upon each operation of lever 54 is a link 64. Link 64 is connected at its lower end to an arm 65 pivoted on a stud 66 screwed into the side frame 20. Arm 65 is slotted at 67 and embraces a pin 68 of an arm 69 on shaft 30 to rock arm 69 counterclockwise upon each operation of lever 54. Arm 69 extends rearwardly, see Figure 5, and is connected by a bail 70 to an arm 71 also pivoted on shaft 30. A spring 72 connected to arm 71 assists spring 59 in maintaining the parts in normal position as determined by the engagement of an arm 61 of lever 69 with a stud 62 fixed in the side frame 20. A rearward extension of arm 71 lies under a collar 73 secured to a wire 74 operated by the universal bar upon typing operations as set forth in the noted patents to Sundstrand.

Wire 74 is the escapement operator and, as shown in Figures 2 and 3, serves, when raised by either the type bar mechanisms or the space bar linkage set forth, to release the escapement dog 19 from the tooth 17 of the escapement wheel 16. Wire 74 is connected at its lower end to an arm of a lever 75 pivoted on plate 11, a spring 76 connected between the lever 75 and dog 19 normally maintaining the dog in engagement with tooth 17.

and an arm of lever 75 against a stud 77 fixed in plate 11. A link 78 connected to dog 19 and provided with a slot 79 embracing a stud 80 of lever 75 provides a one-way driving connection between the dog 19 and lever 75.

From the linkage thus far described, it will be clear that upon depression of space bar 35, lever 54 will be engaged with fluted shaft 23 for a resulting downward movement. This downward movement is transmitted through levers 57, 65, 69 and 71 to an upward motion of wire 74 which through lever 75 and link 78 will disengage dog 19 from the escapement wheel tooth 17. As soon as the lever 54 is free from shaft 23, springs 59, 72 and 76 restore the parts to normal position and dog 19 into engagement with escapement wheel 16. The interval of release of dog 19 is sufficiently short and the inertia of the typing head so great that the dog 19 will be released in ample time to engage the next tooth 17 and so hold the movement of the typing head to one letter space.

The decimal tabulator keys

25 The machine is provided with a plurality, usually ten, decimal tabulator keys 25 to release the carriage from the escapement mechanism and to project a stop to arrest the carriage in a selected position of the next typing column. These keys 25 project one of a group of tabulator stops (not shown) in the manner set forth in Foothorap Patent No. 1,280,697, above, to determine arrest of the carriage. In prior machines of this type it has been the practice to connect these keys 25 to withdraw the escapement dog 19 from escapement wheel 16 at the same time that a tabulator stop was projected. It has been found that the force required in such withdrawal of dog 19 is the major load involved in operating a key 25. 40 The present invention relieves key 25 of such load by a simple and inexpensive connection to the above described space bar mechanism.

Underlying all of the keys 25 is a bail 84 pivoted at 85 to ears 86 of the plate 21. At one side, bail 84 is pivoted to a vertical wire 87 connected at its lower end to an arm of a lever 88 and at its upper end to an arm of a lever 89 pivoted on an upper side plate 22. The other arm of lever 89 is connected to a sliding link 90, the forward end of which is slotted to embrace the upper end of the space bar lever 48. Thus, the depression of any tabulator key 25 will rock the bail 84 to move slide 90 forwardly and rock lever 48 to throw in the power action and to release escapement dog 19 in the manner previously described.

This operation of the power action would normally result in merely a one step advance of the type carriage and not in a tabulating movement. Mechanism to retain the escapement dog 19 disengaged from the escapement wheel 16 and so allow free carriage movement must therefore be provided. This retention of escapement dog 19 is controlled by lever 88 connected to the lower end of wire 87. As shown in Figures 2 and 3, lever 88 is pivoted at 91 to the lower side of plate 10 and extends to the proximity of escapement dog 19. The right end of lever 88 as viewed in these figures is connected by a spring 92 to a slide 93 and is provided with a bent ear 94 overlying a shoulder on slide 93 to normally retain slide 93 depressed. Slide 93 is freely movable vertically on the pivot 18 of dog 19 and on a stud 95 of frame plate 11 and is notched at 96. A stud 97 on dog 19 is normally positioned in notch 96 so that the slide 93 does not interfere with the

normal reengagement of dog 19 with teeth 17 during typing operations.

During a tabulating operation, however, wire 87 when operated by any tabulator key determines release of dog 19 and in addition rocks lever 88 to tension slide 93 upwardly. Slide 93 will, as soon as dog 19 is released, move upwardly to a position blocking the return of dog 19 to its engaging position and the type carriage will thus be free to move to the tabulated position determined as in the above noted Foothorap patent.

The parts will remain in the positions set out above so long as a tabulator key 25 is retained depressed. Upon release of key 25 either at the tabulated position or earlier if desired, the upward movement of wire 87 will move slide 93 downwardly until the notch 96 aligns with stud 97 after which escapement dog 19 is free to re-engage escapement wheel 16.

It is to be noted that due to the one way driving connection between stud 47 of arm 44 and the arm of lever 48, operation of lever 48 by the tabulator keys 25 will not cause a motion of space bar 35 since lever 48 merely moves away from stud 47.

The column tabulator key

The column tabulator key 31, Figures 1 and 5, is provided to advance the carriage directly to a desired column printing position, and is therefore arranged to set up a stop for positioning the carriage in the same manner as do the decimal tabulator keys 25 and must also be held depressed until the carriage reaches the desired position. Key 31, pivoted on the shaft 30, is tensioned by means of a spring 100 to rock clockwise, its movement being limited by means of a slotted bracket 101 affixed to the carriage frame 20. A link 102 connects the key 31 with a lever 103 pivoted at 104 on a bracket 105 secured to the plate 10. The lever 103 overlies a collar 106 secured to the wire 87. Upon depression of the key 31, the member 103 is rocked clockwise about its pivot 104 through link 102 to move the wire 87 downwardly, and thereby actuate the power action to release dog 19 and retain it released in the same manner as when wire 87 is actuated through operation of a tabulator key 25.

The carriage release key

It is desirable at times to free the type carriage from its escapement mechanism to enable the carriage to be positioned at a selected location. For this purpose a carriage release key 29 is provided. This key 29, pivoted on shaft 28, is connected to wire 87 by a stud 107 on the wire engaging in a slot 108 of key 29. This key 29 is not connected to move a tabulator stop into carriage stopping position. Depression of key 29 operates wire 87 to release and hold dog 19 disengaged as above described. The carriage may then be moved to any desired location along the typing line without interference after which release of the key 29 will allow dog 19 to reengage an escapement tooth 17 and hold the carriage in the desired position.

From the above description of the preferred embodiment of the invention, it will be understood that the distinguishing feature of this invention is the provision of a common escapement releasing mechanism for the space bar and the tabulating keys. A further feature is that the carriage will tabulate only so long as a tabulator key is retained depressed.

What is claimed is:

1. In a typewriter having a space bar, an escapement mechanism, and power means controlled by said space bar to momentarily release said escapement mechanism, the combination of a plurality of keys, means operated by each of said keys to control said power means to release said escapement mechanism, a member yieldably connected to said key operated means and operable thereby to retain said escapement mechanism released, and cooperative abutments on said key operated means and said member to restore said member upon release of said key operated means.
- 15 2. In a typewriter having a space bar, an escapement mechanism, power driven means to momentarily disable said escapement mechanism, and means operated by said space bar to control operation of said power means, the combination of a plurality of keys, means common to said keys to actuate at least a part of said space bar operated means to cause operation of said power means, a latch member, connections from said latch member to said common means and means to enable said latch member to retain said escapement mechanism in the resulting disabled condition for so long as one of said keys is operated.
- 30 3. In a typewriting mechanism having a space bar, an escapement mechanism comprising an escapement wheel and a dog normally engaging said wheel, power driven means operable to momentarily release said dog from said escapement wheel, and connections from said space bar to cause actuation of said power means upon operation of any of said keys, a latch plate operable to retain said dog in the released position and yieldable connecting means between said common means and said latch plate to move said latch plate into retaining position when said dog is released by said power means.
- 35 4. In a typewriter or the like having an escapement mechanism comprising an escapement wheel and a holding dog therefor, power means momentarily operable to disengage said dog and said escapement wheel, a member operable to control said power means, a space bar, connections from said space bar to said member, a plurality of keys and a bail common to said keys, the combination of a connection from said bail to said member to operate said member upon depression of any of said keys, a latch to retain said holding dog and said escapement wheel disengaged and a yieldable connection from said common bail to said latch to move said latch into retaining position upon movement of said bail by said keys and disengagement of said wheel and said dog.
- 50 5. In a typewriting machine or the like, the combination of an escapement mechanism, power operable means to release said escapement mechanism, a member normally engaged with a part of said power operable means and movable to control actuation of said power operable means, said member being thereupon disengaged from said part, a space bar, connections from said space bar to operate said member, a plurality of tabulator keys, a connection operable by each of said keys to operate said member, a latch movable to a position wherein it will hold said escapement mechanism released, and a linkage from said connection to said latch to move said latch into hold-
- 55
- 60
- 65
- 70
- 75

ing position upon operation of any of said keys.

6. In a typewriter or the like, a space bar, a plurality of tabulator keys, an escapement mechanism, power means to disable said escapement mechanism, means operable by said space bar or by any of said tabulator keys to cause operation of said power means, a latch operable to retain said escapement mechanism disabled, and means common to said tabulator keys to move said latch to the position to retain said escapement mechanism in disabled condition.

7. In a typewriter, a space bar, a group of tabulator keys, an escapement mechanism comprising a wheel and a dog normally engaged therewith, a linkage operable to disengage said dog from said wheel, a power member to momentarily operate said linkage, a member operable by said space bar or any of said tabulator keys to engage said linkage with said power member and thereby

cause release of said dog from said wheel, a latch plate normally free of said dog and movable to a position wherein said plate will prevent reengagement of said dog with said wheel, and means common to said tabulator keys to yieldingly urge said latch plate into said reengagement preventing position upon operation of any of said tabulator keys.
